MACHINE TOOL FEED CONTROLLING
MEANS

Frank Bednarek, San Francisco, Calif.

Application October 1, 1937, Serial No. 166,827

6 Claims. (Cl. 242—25)

The present invention relates to an improvement in means for controlling the feed of coil winding and like machines, and more particularly to a new and novel form of tool or wire guide feeding arrangement for such a machine.

An object of the invention is to provide in a machine having a rotatable work supporting member and a cooperating tool, a means by which the rate of movement of the tool or wire guide means with respect to the rotatable work may be controlled and adjusted in a simple and convenient manner.

Another object of the invention is to provide a new and novel lead screw arrangement for feeding a tool supporting carriage with respect to a rotatable work supporting member.

Another object of the invention is to provide a new and novel machine which is particularly adapted to the winding of spaced coil windings such as are used in short wave radio sets and the like.

Another object of the invention is to provide a new and novel lead screw arrangement for feeding a tool supporting carriage with respect to a rotatable work supporting member, wherein the rate of feed of the tool supporting carriage may be changed at any point along its travel in a simple and convenient manner.

Other objects and advantages of the invention will be in part evident to those skilled in the art and in part pointed out in the description of the invention as illustrated by the accompanying drawings, wherein there is shown by way of illustration and not of limitation, a preferred embodiment thereof.

In the drawings:

Figure 1 is a plan view of a preferred embodiment of the invention.

Figure 2 is a view similar to Figure 1, with the upper portion cut away to disclose details of construction.

Figure 3 is a vertical sectional view taken along line III—III of Figure 1.

Figure 4 is a slightly enlarged side elevation of the device illustrated in Figure 1, with a portion broken away to disclose details of construction.

Figure 5 is a side elevation of the device illustrated in Figure 1, taken opposite to that of Figure 4, and

Figure 6 is a fragmentary perspective view of the work supporting end of the device.

The device chosen to illustrate the present invention is designed primarily for the winding of short wave coils for radio sets, in which the convolutions of the windings are required to have a

uniform spacing upon different coil supporting forms, or which in some cases require a different spacing between the turns of the coil at different points along a single coil form.

As shown in Figures 1 and 2 of the drawings, the device has a base 10 upon which a coil form supporting chuck 11 is rotatably mounted. Below the chuck 11 the support 10 has transversely extending guides 12 and 13 between which a slideable tool supporting carriage 14 is adapted to move in a line parallel with the axis of work carried by the chuck 11. In Figure 1, the chuck 11 is shown as supporting a coil form 15 of the type having a fluted wire receiving surface and suitable plug terminals 16 arranged at one end. The other end of the coil form 15 has a flange that is adapted to be engaged by an overhanging threaded collar 17 upon the chuck 11 and which serves to firmly secure the coil form 15 thereupon. Mounted upon the base 10 and movable in a straight line transverse to the axis of the coil form 15 there is a slideable member 18 which is adapted to be moved in its path of travel by means of a lead screw 19 that cooperates with a threaded nut 20 carried by the slideable member 18. The lead screw 19 is shown as adapted to be rotated through a beveled gear arrangement 21 by means of a crank 22. The crank 22, in addition to driving the lead screw 19 and the beveled gears 21, also carries a small gear 23 that meshes with a larger gear 24 upon the chuck 11. With this arrangement it will be seen that when the crank 22 is turned, the chuck 11 with the coil forming support 15 will be rotated in a direction to wind wire thereupon, and at the same time the lead screw 19 will be caused to rotate and move the slideable member 18 along its path of travel. The slideable member 18 is guided by an undercut groove in the support 10 and an undercut cleat 25 which is arranged along the other side thereof, and at its outer end it has a supporting arm 26 upon which a diagonally disposed member 27 is pivotally mounted. This diagonally disposed member 27 has a slot 28 that functions, as will be hereinafter pointed out, to control the movement or feed of the tool supporting carriage 14 when the device is in operation. At its outer end the member 27 is secured in a fixed position with respect to the slideable support 18 by means of a positioning rod 29 which is pivotally mounted upon the slideable member 18 by a hinged connection 30. At its free end the positioning rod 29 slides through a clamping member 31 carried by the diagonally disposed member 27, and when tightened thereupon by means of a thumb screw 32

32 upon the clamp 31, it is adapted to hold the diagonally disposed member 27 at any desired angular position. The diagonally disposed member 27 is shown as extending under the tool supporting carriage 14 and as pivoted at a point 33 beyond the center thereof. The slot 28 of the diagonally disposed member 27 likewise extends beyond the center of the slideable tool supporting carriage 14, and cooperating with this slot 28 the 10 slideable tool supporting carriage 14 has a downwardly projecting member 34 which is adapted to slide along the slot 28 as the diagonally disposed member 27 is carried in a straight line by a movement of the slideable member 18 in response to a rotation of the lead screw 19. When the device is used to wind coils, the slideable tool carrying support 14 is provided with a wire guide supporting arm 35 having wire guiding rollers 36 at its outer end. The member 35 is shown as 20 adjustably secured upon a post 37 of the tool supporting carriage 14 by a thumb screw 38.

In addition to the above features, the drawings also show the support 10 as having a spindle 39 upon which a spool of wire 40 is adapted 25 to be secured, and positioned between the spool of wire 40 and the wire guiding rollers 36 there is a wire tensioning means 41 which is to be described in more detail hereinafter. With this arrangement, as shown in Figure 1 of the drawings, a wire, designated by the numeral 42, is taken from the spool 40 passed under a rotatable guide roller 43 of the tensioning means 41, and under and over the wire guiding rollers 36 upon the supporting arm 35 and finally wound upon 30 the coil receiving form 15 with a spacing which will be determined by the disposition of the diagonally disposed member 27. At this point it may be pointed out that in the device illustrated, the lead screw has a pitch of sixteen threads to the 35 inch and it is driven through the beveled gears 21 at a 1 to 1 ratio with respect to the crank 22, and the gears 23 and 24, which serve to drive the chuck 11, have a ratio of 1 to 4. As a result, when the diagonally disposed member 27 which 40 controls the movements of the slideable tool carrying support 14 is disposed at an angle of 45 degrees, the pitch of the winding upon the coil form 14 will be 4 turns to the inch throughout its length.

Upon referring to Figure 3 of the drawings, 50 it will be noted that the coil receiving form 15 is open at one end and that the chuck 11 has a central opening 44 over which the open end of the coil form 15 is adapted to be disposed. This opening in the chuck 11 permits an operator to pull 55 the end of the wire 42 through a hole made in the coil form and connect it with one or the other of the plug contacts 16 at the outer end of the coil form 15 without removing the coil form from the chuck 11. After the desired number 60 of turns at the particular spacing have been placed upon the coil form 15, the operator will then make another hole in the coil form 15 and pull the remaining end of that particular coil section through said hole and connect it to the 65 proper terminal 16. Should the coil form be one of the type having two windings of different spacings, the operator can now, by making a further hole in the coil form 15, start and complete a second winding upon the coil form with 70 any different desired spacing of the windings by merely adjusting the angle of the member 27 and proceeding as before.

Reference is now made to Figures 4 and 5 of the drawings, for a description of the wire tensioning means hereinbefore referred to. As shown 75

in these figures of the drawings, the spindle 39 upon which the spool of wire 40 is adapted to be mounted has a drum 45 with which a pair of clamping brake shoes 46 cooperate. The brake shoes 46 are adjustable into braking relation with the drum 45 by means of a spring 47 and an adjustable thumb screw 48. Arranged between the spindle 39 and the coil form supporting chuck 11, the support 10 carries a pivotally mounted shaft 49 having a crank arm 50 upon the end 10 of which there is a transversely extending stub shaft 51 that carries the slideable and rotatable wire engaging guide 43. At the outer end of the shaft 49 there is a transversely extending head 52 that is disposed between opposed levers 53 and 54 which are biased toward each other by a spring 55 and a clamping rod 56 upon the outer end of which, for the purpose of varying the compression of the spring 55, there is a thumb nut 57. With this arrangement it will be seen that as 20 the rotatable shaft 49 is rocked one way or the other, the transversely extending head 52 thereupon will engage the oppositely disposed clamping members 53 and 54 and thus tend to prevent too great a displacement of the wire engaging guide roller 43 as the wire 42 is drawn therealong during a winding operation. With this arrangement it will be seen that the wire 42 may be taken from the top of the spool 40, 25 as shown in Figure 5 of the drawings, and passed under the wire engaging guide roller 43, or it may be taken off the bottom of the spool 40 and passed over the wire engaging guide roller 43 upon the tensioning means 41.

Reference is now made to Figure 6 of the drawings, wherein the slideable tool supporting carriage 14 is shown as having a cutting tool mounted thereupon. In this arrangement the tool supporting carriage is shown as having a vertically extending post 58 disposed at the other side of 40 the coil form 15 in which a bar 59 is slidably secured by a thumb screw 60, and at the outer end of the bar 59 there is a cutting tool 61 that is adapted to be adjusted into groove cutting relation 45 with the coil form 15 when the latter is rotated with the chuck 11. In the event that the device is equipped with a cutting tool, as shown in this figure of the drawings, by properly adjusting the angle of the diagonally disposed member 27, it will be possible to provide for any desired feed of the cutting tool 61 with respect to work carried by the chuck 11, and thus cut 50 grooves upon the work for the reception of the turns of a coil or for any other purpose.

While I have, for the sake of clearness and in order to disclose the invention so that the same can be readily understood, described and illustrated specific devices and arrangements, I desire to have it understood that this invention is not limited to the specific means disclosed, but may be embodied in other ways that will suggest themselves to persons skilled in the art. It is believed that this invention is new and it is desired to claim it so that all such changes as 60 come within the scope of the appended claims are 65 to be considered as part of this invention.

Having thus described my invention, what I claim and desire to secure by Letters Patent is—

1. In a device of the character described, the combination of a rotatable work supporting member, a tool support adjacent said member, a slideable carriage for said tool support movable in a line parallel with the axis of said rotatable work supporting member and having a slot engaging extension, a carriage driving member having an 70 75 80 85 90 95

angularly disposed slot into which said slot engaging member is slidably disposed, said carriage driving member being movable in a path tangent to the axis of said work supporting member, and 5 means for rotating said work supporting member and simultaneously moving said carriage driving member with respect to said tool supporting carriage, whereby said slidable carriage will move parallel to the axis of said rotatable work sup- 10 porting member at a relative speed as determined by the angular disposition of the slot on said carriage driving member.

2. In a device of the character described, the combination of a rotatable work supporting member, a tool support adjacent said member, a carriage for said tool support slidably mounted to move in a line parallel with the axis of said rotatable work supporting member and having a slot engaging extension, a driving means for 15 said carriage, said driving means comprising a slidable member having an angularly disposed slot into which said extension is extended, said slidable member and its angular slot being movable in a path tangent to the axis of said work 20 supporting member, a lead screw extending outwardly from said work supporting member and connected in threaded engagement with the slid- 25 able member of said driving means, and means for rotating said work supporting member and simultaneously turning said lead screw, whereby 30 the tool supporting carriage will move parallel to the axis of said rotatable work supporting member at a relative speed as determined by the angular disposition of the slot in the slidable 35 member of said driving means.

3. In a device of the character described, the combination of a support, a rotatable work holding means mounted upon said support, a tool support adapted to move parallel to the axis of 40 said rotatable work holding means, a carriage movable in a line parallel with the axis of said rotatable work holding means upon which said tool support is mounted, a second carriage mounted upon said support adapted to move in 45 a straight line transverse to the direction of travel of said first carriage, an angularly adjustable member upon said second carriage having a slid- 50 able driving connection with the carriage upon which said tool support is mounted, a lead screw extending at a right angle to the axis of said work holding means, a threaded means carried by said second carriage engaging said lead screw, and means for driving said rotatable work holding means and simultaneously turning said 55 lead screw, whereby said first carriage will move parallel to the work upon said rotatable work holding means as the work is rotated and said second carriage moves at a right angle with respect thereto in response to a turning of said 60 lead screw.

4. In a device of the character described, the combination of a foundation forming support, a horizontally disposed rotatable work holding means upon said support, a slid- 65 able tool carrying support mounted below said rotatable work holding means and movable parallel to the axis thereof, a slid- 70 able member mounted upon said foundation forming support movable in a line at

a right angle to the direction of movement of said slidable tool carrying support, means for rotating said rotatable work holding means, a lead screw extending at a right angle to the axis of said work holding means and connected in 5 threaded driving relation with said slidable member, a slot engaging projection upon said slidable tool carrying support, an angularly adjustable arm upon said slidable member having a straight slot formed thereupon and engaging the slot en- 10 gaging projection upon said slidable tool carrying support and adapted to move in a path at a right angle to the line of movement of said slid- 15 able tool carrying support in response to a turning of said lead screw, whereby said slidable tool carrying support will move axially relative to the work at a rate of movement dependent upon the angular disposition of the adjustable arm upon said slidable member.

5. In a device of the character described, the combination of a main support, a tool carrying support, a pair of spaced parallel guides between which said tool carrying support is slidably mounted, a second slidable member mounted upon said main support movable in a line at a 20 right angle to the direction of movement of said slidable tool carrying support, a lead screw extending at a right angle to the direction of movement of said slidable tool carrying support and connected in threaded driving relation with said 25 second slidable member, a slot engaging projection upon said slidable tool carrying support, an arm upon said second slidable member having a slot formed thereupon disposed at an angle to the direction of movement of said slidable tool 30 carrying support and said second slidable member and receiving the slot engaging projection upon said slidable tool carrying support, whereby said slidable tool carrying support will move between said spaced parallel guides at a rate of 35 movement dependent upon the angular disposition of the arm upon said slidable member.

6. In a coil winding device of the character described, the combination of a support, a horizontally disposed rotatable coil form holding means 45 upon said support, a wire guiding means mounted adjacent said coil form holding means and movable parallel to the axis thereof, a slid- 50 able member mounted upon said support movable in a line at a right angle to the direction of movement of said wire guiding means, means for rotating said coil form holding means, a lead screw extending outwardly from said coil form holding means and connected in threaded driving relation with said slidable member, a slot engaging 55 projection carried by said wire guiding means, an angularly adjustable arm upon said slid- 60 able member having a slot formed thereupon into which the slot engaging projection upon said wire guiding means extends adapted to move in a path at a right angle to the line of movement of said wire guiding means in response to a turning of said lead screw, whereby said wire guiding means will move axially relative to a coil form upon said holding means at a rate of movement 65 dependent upon the angular adjustment of the arm upon said slidable member.

FRANK BEDNAREK.
